FIG. 6.

ATTEST,

John H. Redstone
W. C. Whitman

INVENTOR,

Emma J. Whitman

UNITED STATES PATENT OFFICE.

EMMA J. WHITMAN, OF OAKLAND, CALIFORNIA.

SASH-FASTENER.

SPECIFICATION forming part of Letters Patent No. 372,349, dated November 1, 1887.

Application filed March 24, 1887. Serial No. 232,346. (No model.)

To all whom it may concern:

Be it known that I, EMMA J. WHITMAN, a citizen of the United States, residing in Oakland, in the county of Alameda and State of California, have invented a new and useful Window Lock and Adjuster, of which the following is a specification, reference being had to the accompanying drawings and the letters marked thereon.

10 My invention relates to improvements in window locks and adjusters.

Figure 1 is a front elevation of a window with my improvement attached. Fig. 2 is a sectional view showing the same cut vertically 15 through the center of the frame and sash. Fig. 3 is an enlarged front elevation of my improved lock. Fig. 4 is a side elevation of the same. Fig. 5 is a plan view of the bolt that operates in the window-frame. Fig. 6 is a sectional plan view of my improved lock and adjuster.

20 A represents the lock-bolt; B, the sleeve lock-bolt set-screw; C, the thumb-piece of the set-screw; D, the bolt that catches in the window-frame; E, the collar that forms the stop for the set-screw; F, the outer sleeve that forms the case for the lock-bolt; G, the attaching-plate for the top of the top rail of the lower sash; H, the attaching-plate for the front of 25 the top rail of the lower sash.

30 I represents the lock-plate for the upper sash.

J represents the sockets for the slide-bolt D in the side of the window-frame to lock the 35 lower sash.

K represents the upper sash, and L the lower sash.

40 The following is the construction of the same: The outer case, F, and the attaching-plates G and H are cast in one piece. The lock-bolt A is tapped to receive the set-screw

B, and the threads are cut so as to give a quick action. I generally form the thumb-piece C small in diameter and long, as shown in the drawings, although I sometimes vary the construction of the same as may be required. 45

I form the lock-plate I of thin metal, and perforate it to receive the lock-bolt A, as shown in Figs. 1 and 3.

The following is the operation of the same: 50 In lowering the upper sash, K, the bolt A is withdrawn from the lock-plate I by turning the set-screw B back. Then the sash is let down until the bolt A is opposite to the perforation designed for adjustment of the sash to the required opening. The set-screw A is then turned forward, setting the bolt into the proper perforation of the plate I. When the lower sash is to be raised or adjusted, the slide-bolt 55 D is adjusted in the sockets J, by which means 60 it is held at any required point. By tightening the bolt A the two sashes K and L are set firmly against their bearings, and all rattling or shaking is avoided.

Having thus described my invention, what 65 I claim, and desire to secure by Letters Patent, is—

In window-stops, a sash-fastener consisting of the case F, having attaching-plates formed integral therewith, a bolt arranged in said case 70 and internally threaded, the screw B, engaging the threads of the bolt and having a stop-collar, E, and a thumb-piece, C, the sliding bolt D passing beneath the said screw B and case, and adapted to move in a plane at right angles with the bolt A, substantially as specified. 75

EMMA J. WHITMAN.

Witnesses:

JOHN H. REDSTONE,
W. C. WHITMAN.
